CLAIM

The ornamental design for article for holding writing instruments, as shown and described.

DESCRIPTION

FIG. 1 is a perspective view of an article for holding writing instruments showing my new design;

FIG. 2 is a front elevational view thereof shown on an enlarged scale;

FIG. 3 is a rear elevational view thereof;

FIG. 4 is a bottom plan view thereof;

FIG. 5 is a top plan view thereof;

FIG. 6 is an end elevational view thereof; and

FIG. 7 is an end elevational view of the end opposite that shown in FIG. 7;

The broken line showing of human hand and writing instrument in FIG. 1 is for illustrative purposes only and forms no part of the claimed design.

FIG. 4

FIG. 5

FIG. 6

FIG. 7
